UNITED STATES PATENT OFFICE.

CARL F. GRÜNER, OF NEW YORK, N. Y.

STREET-SWEEPING MACHINE.

SPECIFICATION forming part of Letters Patent No. 338,225, dated March 16, 1886.

Application filed March 17, 1884. Serial No. 124,408. (No model.)

To all whom it may concern:

Be it known that I, CARL F. GRÜNER, of the city, county, and State of New York, have invented certain new and useful Improvements 5 in Street-Sweeping Machines, of which the following is a specification.

This invention has reference to an improved machine for sweeping streets and laying the dust at the same time, by a proper supply of moisture; and the invention consists of a wheel-supported box having a revolving brush at its rear end, a scoop formed of a series of pivoted and curved teeth in front of said box, the end tooth having vertical flanges, a small quicker- 15 revolving brush, and a small deflecting-plate above the main brush and scoop, and an elevator 15 that receives the dust and discharges the same into a storage-receptacle of the box. At the bottom of the box is a scoop formed of curved 20 and pivoted teeth for collecting the tin cans. At the lower front end of the same are arranged 25 openings, which are connected by a vertical channel with a water-reservoir above the dust-receptacle. A shorter tapering side brush is arranged at the front part of the machine, for 30 sweeping the gutters, and adapted to be raised and moved forward out of the way.

In the accompanying drawings, Figure 1 represents a vertical longitudinal section of 30 my improved street-sweeping machine; Fig. 1^a, a detail of one of the teeth of the main scoop; Fig. 2, a side elevation of the machine; Fig. 3, a front elevation of the same. Figs. 4 and 5 are details of the dust-conveying elevator; and Figs. 6 and 7 are a side view and 35 plan of the machine, showing the gutter-sweeping brush in raised position.

Similar letters of reference indicate corresponding parts.

40 A in the drawings represents a wheeled storage-box of suitable size, that is drawn by horses applied to a shaft at the front end of the box. A revolving main brush, B, at the rear end of the storage-box A, lifts the dust along the scoop C, that is pivoted close to the brush B, and composed of a number of curved teeth, *a a*, which are arranged closely to each other. The teeth or tines *a a* pass readily over obstructions on the street without interfering with 45 the operation of the brush. The end teeth *a a* have flanges *a'* at one side, that move along

the side walls of the box A, as shown in Fig. 2. A second brush, B', is arranged above the main brush B, and revolved in opposite direction to and at greater speed than the main brush. The brush B' takes up the dust and moves it along the fixed concave scoop C', above the articulated scoop C, dropping it into the cups of an elevator, D.

The elevator D is constructed of two endless 60 belts, *d*, to which are riveted the cups *d'*, the cups being connected by plates *d''* of narrow interlocking flexible links *d''*, as shown in Figs. 4 and 5, whereby the passage of dust to the interior of the elevator is prevented, and the 65 cups enabled to pass readily over the guide and drive-pulleys D' D².

The elevator D conveys the dust into the storage bin or receptacle A', at the front part of the box A, which is provided with drop- 70 doors at the bottom, so that the contents can be removed when the receptacle is filled.

Above the storage-box A' is arranged a wa- 75 ter-receptacle, A², which communicates by a narrow vertical channel, A³, with small open- 80 ings *e*, at the lower front part of the receptacle A', whereby the water is discharged in jets on the street, so that the same is moistened to some extent, and the dirt taken up without creating too much dust.

Below the bottom of the storage-receptacle A' is arranged a second articulated scoop, F, which is also made of curved teeth *f*, that are pivoted to the bottom of the box A, and prevented from dropping below a certain position 85 by a transverse rod, *f'*, applied to adjustable side straps, *f''*. The teeth *f* extend forward and are curved upward at their front ends, so as to clear obstructions on the street, but strike tin cans and similar light bodies, and cause 90 them by repeatedly jostling to be lifted and dropped back into the scoop, where they are gathered at the rear part of the same and removed from time to time. The end teeth *f* are provided with vertical flanges *f''*, that retain the cans on the scoop. When the sweep- 95 ing operation is to be interrupted, the front wheel, *b*, is raised by its hand-wheel and screw, whereby the front part of the box A is lowered and the rear part, with its brush, raised 100 above the pavement. A brush, E, with an enlarged end, is arranged at the front part of the

box and extended laterally at an angle of inclination to the axis of the machine, the side brush being designed to sweep the gutters and throw the dirt inward into the path of the main brush B.

The spindle of the gutter-brush E is supported in bearings of a lever-arm, E', that can be raised or lowered by a suitable lever mechanism. When raised, the brush assumes the

- 5 o position shown in Fig. 6. The upper hinged section of the lever E' is then swung inwardly in front of the box A, so that the gutter-brush E is out of the way when going to or from the work, as shown in Fig. 7. A sliding bolt, E², supports the lever E' when the same is raised. A slide-bolt, e', locks the hinged upper section of the lever into line with the lower section of the same when the brush is lowered for use.

Any other suitable mechanism for raising o the gutter-sweeping brush E, and then swinging the same inward at the front part of the box A, may be used, as I do not desire to confine myself to the special construction shown.

The brushes B, B', and E, also the elevator 5 D, are operated by belt-and-pulley transmission from the axle of the main wheels, as shown clearly in the drawings.

The street-sweeping machine serves for sweeping the gutters and streets and for gathering tin cans and other larger articles. The dust is stored away in the receptacle and discharged from time to time, and then carted away.

The machine may also be constructed on a 5 smaller scale, but without the gutter-brush and the scoop for gathering tin cans, in which it is moved by hand, and forms a convenient machine for sweeping the foot-walks of parks and public places.

Having thus described my invention, I claim as new and desire to secure by Letters Patent—

1. The combination of a wheeled storage-box, A, a rotating main brush, B, at the rear end of said box, a scoop, C, formed of a number of curved and pivoted teeth, a, arranged 45 close to each other, the end teeth having vertical flanges a', a fixed concave scoop, C', located immediately above the pivoted scoop, a take-up brush, B', and an elevator, D, substantially as set forth.

2. In a street-sweeping machine, the combination, with a wheeled storage-box, A, of a forward-extending curved scoop, F, hinged to the bottom of the box A, and adapted to receive tin cans, substantially as specified.

3. The combination of a wheeled storage-box, A, with a forward-extending scoop, F, formed of a series of curved and pivoted teeth, f, the end teeth having vertical flanges f', and a transverse supporting-bar, f', guided in 60 slotted straps f², substantially as described.

4. In a street-sweeping machine, the combination, with the vehicle-body, of a stub-shaft projecting laterally therefrom, a lever pivoted at one end to said shaft, a bolt attached to said 65 body for supporting said lever in elevated position, a gutter-cleaning brush, the spindle of which turns in a bearing at the outer end of said lever, the outer end of said lever being hinged to the main body thereof, whereby the 70 brush may be swung to the front or side of the sweeper, and a bolt for locking the two parts of said lever in line, substantially as described.

In testimony that I claim the foregoing as my invention I have signed my name in presence of two subscribing witnesses.

CARL F. GRÜNER.
